UNITED STATES PATENT OFFICE.

HENRY NEUMAN, OF SCAPPOOSE, OREGON.

PEN-POINT RELEASER.

1,292,021.

Specification of Letters Patent. Patented Jan. 21, 1919.

Application filed May 23, 1918. Serial No. 236,186.

To all whom it may concern:

Be it known that I, HENRY NEUMAN, a citizen of the United States of America, residing at Scappoose, in the county of Columbia and State of Oregon, have invented 5 certain new and useful Improvements in Pen-Point Releasers, of which the following is a specification, reference being had therein to the accompanying drawing.

10 This invention relates to a pen point releaser and has for its principal object the production of a device which is so arranged as to firmly hold the pen point when the same is in use although upon the pressing 15 of the operating rod, the pen point will be released.

Another object of this invention is the production of a pen point releaser wherein the clamping jaw is carried upon the rock- 20 ing yoke so that the clamping jaw may be swung downwardly from engagement with the pen point, thereby releasing the same.

With these and other objects in view, this invention consists of certain novel construc- 25 tions, combinations and arrangements of parts as will be hereinafter more fully described and claimed.

In the accompanying drawings:

Figure 1 is a detail perspective view of 30 the device illustrating the same in use.

Fig. 2 is a central longitudinal section through the pen point releaser, a portion of the holder being broken away.

Fig. 3 is a plan view of the clamping 35 jaw, portions of the elements used in connection with the clamping jaw being shown in section and also in elevation.

Fig. 4 is a detail perspective view of the clamping jaw, the sleeve and the rocking 40 yoke.

Fig. 5 is a sectional view through the clamping jaw.

Fig. 6 is a longitudinal section through the spring housing, illustrating the means 45 by which the rod is normally urged in one direction.

Referring to the accompanying drawings by numerals, it will be seen that the pen point releaser comprises a holder 1 having 50 the longitudinal bore 2 extending there- through. A neck 3 is formed upon the holder 1 so as to carry the tube 4 in which there is positioned a coil spring 5. A rod 6 is reciprocally mounted through the bore 55 2 and extends through the coil spring 5 as shown clearly in Fig. 6 so as to have its

threaded end 7 carried by the knob 8. The coil spring 5 bears upon one end of the neck 3 and at its opposite end upon the inner end of the knob 8 so as to normally urge the 60 knob 8 in one direction and consequently draw the rod 6 in the same direction.

The usual sleeve 9 is mounted upon the reduced portion 10 formed upon the opposite end of the holder 1, while the ordinary grip 65 11 is carried upon the sleeve 9, which grip 11 is generally formed of rubber or some similar material.

The cylindrical frame 12 is mounted upon the holder 1 within the sleeve 9 as shown 70 clearly in Fig. 2. This cylindrical frame 12 has a semi-circular extension 13 extending therefrom which projects for a considerable distance beyond the abutment tongue 14 which has an abutment lip 15 at right angles and is spaced from the extension 13. The rocking yoke comprises a bridge 16 having the parallel side arms 17 extending at right angles thereto and these side arms 17 terminate in the outwardly extending ends 75 18. These outwardly extending ends 18 are pivotally mounted upon the extension 13 of the cylindrical frame 12 and in this manner, it will be seen that the rocking frame will be pivotally supported. The clamping 80 jaw 19 is formed from a blank of sheet metal and although elongated is substantially semi-circular in cross section adjacent its forward end. Adjacent the inner end of the clamping jaw 19 there is formed a pair 90 of parallel walls 20 of considerable less breadth than the breadth of the forward end of the clamping jaw. The bridge 16 of the rocking yoke passes through the walls 20 and by having the walls 20 parallel, it will 95 be seen that the parallel arms 17 of the rocking yoke may be passed thereby without interference. Furthermore, it will be seen that the parallel walls 20 are positioned within planes extending along the side surfaces of the forward end of the clamping jaw 19 and the arm 17 of the rocking yoke

100 will also be positioned within planes so as to freely move without binding the clamping jaw upon the extension 13 of the cylindrical frame 12. The rod 6 is offset as shown at 105 21 thereby providing an offset extension 22 which is secured to the under side of the clamping jaw 19 as by soldering or in any other suitable manner.

When the pen point releaser is in operation, it is obvious as above explained, that

the rod 6 will be urged in one direction by the spring 5. Since this rod 6 has its offset extension 22 fixedly mounted upon the clamping jaw 19, this clamping jaw will be urged toward the inner end of the sleeve 9 and toward the cylindrical frame 12. The inward movement of the clamping jaw 9 will be limited at all times by its abutment against the depending lip 15 of the abutment 5 tongue 14 as shown in Figs. 2, 3 and 4. As a consequence, it will be seen that the rocking yoke 17 will be prevented from swinging over so far as to cause the clamping jaw to bind in such a position within the sleeve 9 10 as to prevent its efficient operation. When it is desired to insert a pen point in the holder, the knob 8 is pushed inwardly into the tube 4 so as to compress the coil spring 5. This action will move the rod 6 forwardly and as 15 a consequence will cause the clamping jaw 19 to be swung forwardly and downwardly from the sleeve 9 at which time a pen point 23 may be positioned so as to bear upon the inner side of the sleeve 9 and at this time the 20 knob 8 may be released. The coil spring 5 will again expand to its normal position thus causing the knob to draw upon the rod 6 and as a consequence, the clamping jaw 19 will be swung upon the rocking yoke 17 and 25 into a binding engagement with the pen point 23 as shown in Fig. 2. In this manner, it will be seen that the pen point will be releasably retained very firmly in position for use. When it is desired to release the 30 pen point 23, the rod is again moved forwardly by pressure upon the knob 8, thus causing the clamping jaw to move forwardly and downwardly so as to provide considerable space between the clamping jaw and 35 the sleeve 9, which action will cause the pen point 23 to be released so as to cause the pen point to drop from engagement with the sleeve and the clamping jaw. Thus it will be seen that the pen point may be more eas- 40 ily released than with the ordinary releasing pen holders now in use for the pen holders now used merely cause the clamping elements to slide forwardly in the same parallel plane it normally bears with respect to 45 its retaining sleeve so that in case the pen point rusts within the retaining sleeve, it is usually necessary to grip the pen point and pull the same from engagement with the holder. In this device, however, the moving 50 of the clamping jaw 19 will cause its upper top portion to be spaced for a considerable distance from the inner portion of the sleeve 9 in alignment therewith and the pen point will either drop from the device or 55 upon being struck will be removed in case it has rusted in position.

From the foregoing description, it will be seen that a very efficient pen point releaser has been provided which may be cheaply 60 manufactured owing to its being formed of

sheet metal and which is so constructed as to positively retain the pen point in position although upon the movement of the clamping jaw to one side the pen point may be freed without the necessity of gripping 70 the pen point separately after it is released.

What is claimed is:

1. In a device of the class described, the combination of a pen holder, a frame carried by said pen holder, a clamping jaw pivotally mounted upon said frame, a sleeve carried by said pen holder, said clamping jaw being adapted to releasably hold a pen point in engagement with said sleeve, and means for swinging said pen point forwardly and 75 away from the clamping portion of said sleeve whereby said pen point may be released.

2. In a device of the class described, the combination of a pen holder, a sleeve carried upon said pen holder, a frame carried by said pen holder within said sleeve, a rocking yoke carried upon said frame, a clamping jaw mounted upon said rocking yoke, and means for moving said clamping jaw, said 80 clamping jaw being adapted to releasably retain a pen point in engagement with said sleeve, said means being adapted to move said clamping jaw upon the swinging of said rocking yoke whereby said clamping 85 jaw will be moved forwardly and away from the clamping portion of said sleeve thereby permitting the pen point to be released.

3. In a device of the class described, the combination of a pen holder, a sleeve carried upon said pen holder, a frame carried by said pen holder within said sleeve, a rocking yoke pivotally mounted upon said frame, a clamping jaw pivotally mounted upon said 90 rocking yoke, means for normally urging said clamping jaw in one direction for releasably retaining a pen point in engagement with said sleeve, and means for limiting the movement of said clamping jaw in one direction, said first mentioned means being capable of operation for moving said clamping jaw upon the swinging of said 95 rocking yoke whereby said clamping jaw will be swung away from the gripping portions of said sleeve so as to provide a considerable space for permitting a pen point to be dropped from engagement with said sleeve.

4. In a device of the class described, the combination of a pen holder, a sleeve carried 100 upon said pen holder, a cylindrical frame carried by said pen holder within said sleeve, an extension projecting from said cylindrical frame, a rocking yoke pivotally mounted upon said extension, a clamping 105 jaw pivotally mounted upon said rocking yoke, and means for urging said clamping jaw in one direction whereby a pen point will be releasably retained in engagement with said sleeve, said means being adapted 110 to 115

120

125

130

to operate to swing said clamping jaw away from the gripping portion of said sleeve whereby a pen point may be released.

5. In a device of the class described, the 5 combination of a pen holder, a sleeve carried by said pen holder, a cylindrical frame carried by said pen holder, an extension projecting from said cylindrical frame, an abutment tongue extending from said cylindrical frame, an abutment lip formed upon said tongue, a rocking yoke pivotally mounted upon said extension, a clamping jaw pivotally mounted upon said rocking yoke, and means for urging said clamping jaw in one 10 direction whereby said clamping jaw will normally bear upon said abutment lip whereby its movement in one direction will be limited, said clamping jaw being adapted to releasably retain a pen point in engagement with said sleeve, said means being adapted to operate so as to swing said clamping jaw upon said rocking yoke and away from said clamping portion of said sleeve thereby permitting the pen point to be 15 ejected.

6. In a device of the class described, the 30 combination of a pen holder, a sleeve carried upon said pen holder, a frame carried by said pen holder within said sleeve, an abutment tongue extending from said frame and terminating in an abutment lip, a rocking yoke pivotally mounted upon said frame, a clamping jaw pivotally mounted upon said rocking yoke, and means for normally urging said clamping jaw in one direction 35 whereby said clamping jaw will abut against said lip so as to be limited in its movement in one direction at which time said clamping jaw may releasably retain a pen point within 40 said sleeve, said means being adapted to be operated so as to swing said clamping jaw upon said yoke and away from the clamping portion of said sleeve and thereby permitting the pen point to be released.

45 7. In a device of the class described, the combination of a pen holder, a sleeve carried upon said pen holder, a frame carried by said pen holder within said sleeve, said frame having an extension projecting therefrom, a rocking yoke comprising a bridge having parallel side arms terminating in outwardly extending portions, said ends being pivotally mounted upon said extension, a clamping jaw pivotally mounted upon said 50 rocking yoke, and means for normally urging said clamping jaw in one direction, whereby said clamping jaw will releasably retain a pen point in engagement with said sleeve, said means being adapted to operate 55 so as to swing said clamping jaw upon said rocking yoke for causing said clamping jaw to be swung away for a spaced distance from the inner clamping portion of said sleeve thereby permitting a pen point to be 60 released.

8. In a device of the class described, the combination of a pen holder, a sleeve carried upon said pen holder, a frame carried by said pen holder within said sleeve, said frame having an extension projecting therefrom, a rocking yoke comprising a bridge having parallel side arms terminating in outwardly extending portions, said ends being pivotally mounted upon said extension, a clamping jaw pivotally mounted upon said rocking yoke, means for normally urging said clamping jaw in one direction, said first-named means being adapted to operate so as to swing said clamping jaw upon said rocking yoke for causing said clamping jaw to be swung away for a spaced distance from the inner clamping portion of said sleeve thereby permitting a pen point to be released.

9. In a device of the class described, the combination of a pen holder, a sleeve carried upon said pen holder, a frame carried by said pen holder within said sleeve, said frame having an extension projecting therefrom, a rocking yoke comprising a bridge having parallel side arms terminating in outwardly extending ends, said ends being pivotally mounted upon said extension, a clamping jaw pivotally mounted upon said rocking yoke, means for normally urging said clamping jaw in one direction whereby 100 said clamping jaw will releasably retain a pen point in engagement with said sleeve, and an abutment tongue extending from said frame and terminating in an abutment lip, said clamping jaw abutting against said lip so as to be limited in its movement in one direction, said means being adapted to operate so as to swing said clamping jaw upon said rocking yoke for causing said clamping jaw to be swung away for a spaced distance 105 from the inner clamping portion of said sleeve thereby permitting a pen point to be released.

10. In a device of the class described, the combination of a pen holder, a sleeve carried upon said pen holder, a frame carried by said pen holder within said sleeve, a rocking yoke pivotally mounted upon said frame, a clamping jaw comprising an elongated body which is substantially semi-circular adjacent 115 its forward end, parallel walls formed upon the inner end of said clamping jaw, said clamping jaw provided with a pivot passing through its parallel walls, and means for normally urging said clamping jaw in one 120 direction so as to releasably hold a pen point in engagement with said sleeve, said means being adapted to be operated so as to swing said clamping jaw upon said yoke away from the inner clamping portion of 125 130

said sleeve thereby permitting a pen point to be released.

11. In a device of the class described, the combination of a pen holder, a sleeve carried upon said pen holder, a frame carried by said pen holder within said sleeve, an extension projecting from said frame, a rocking yoke pivotally mounted upon said extension, a clamping jaw comprising a semi-circular body having parallel walls adjacent one end, said rocking yoke passing through said side walls for pivotally supporting said clamping jaw, and means for normally urging said clamping jaw in one direction so as to releasably retain a pen point, said means being adapted to operate so as to swing said clamping jaw forwardly and away from the clamping portion of said sleeve in alinement with the clamping portion of said jaw thereby permitting a pen point to be released.

12. In a device of the class described, the combination of a pen holder, a sleeve carried upon said pen holder, a frame carried by said pen holder within said sleeve, an extension projecting from said frame, a rocking yoke pivotally mounted upon said extension, a clamping jaw comprising a semi-circular body having parallel walls adjacent one end, said rocking yoke passing through said side walls for pivotally supporting said clamping jaw, and means for normally urging said clamping jaw in one direction so as to releasably retain a pen point, means for limiting the movement of said clamping jaw in one direction, said means being adapted to operate so as to swing said clamping jaw forwardly and away from the clamping portion of said sleeve in alinement with the clamping portion of said jaw thereby permitting a pen point to be released.

13. In a device of the class described, the combination of a pen holder, a sleeve carried upon said pen holder, a frame carried by said pen holder within said sleeve, an extension projecting from said frame, a rocking yoke pivotally mounted upon said extension, a clamping jaw comprising a semi-circular body having parallel walls adjacent one end, said rocking yoke passing through said side walls for pivotally supporting said clamping jaw, and means for normally urging said clamping jaw in one direction so as to releasably retain a pen point, an abutment tongue extending from said frame and terminating in an abutment lip, said clamping jaw being adapted to abut against said lip for being limited in its movement in one direction, said means being adapted to operate so as to swing said clamping jaw for-

wardly and away from the clamping portion of said sleeve in alinement with the clamping portion of said jaw thereby permitting a pen point to be released.

65

14. In a device of the class described, the combination of a pen holder, a sleeve carried upon said pen holder, a frame carried by said pen holder within said sleeve, an extension projecting from said frame, a rocking yoke comprising a bridge having parallel arms terminating in outwardly extending ends, said ends being pivotally mounted upon said extension, a clamping jaw having parallel side walls; said bridge extending through said side walls for pivotally supporting said clamping jaw, an abutment tongue extending from said frame and terminating in an abutment lip, said clamping jaw normally bearing upon said lip whereby its movement in one direction will be limited, and means for normally urging said jaw in one direction for releasably retaining a pen point in alinement with said sleeve, and said means being adapted to operate so as to swing said clamping jaw upon said yoke forwardly and away from the clamping portion of said sleeve in alinement with the clamping portion of said jaw whereby a pen point will be released.

80

15. In a device of the class described, the combination of a pen holder, a sleeve carried upon said pen holder, a frame carried by said pen holder within said sleeve, an extension projecting from said frame, a rocking yoke comprising a bridge having parallel arms terminating in outwardly extending ends, said ends being pivotally mounted upon said extension, a clamping jaw having parallel side walls, said bridge extending through said side walls for pivotally supporting said clamping jaw, an abutment tongue extending from said frame and terminating in an abutment lip, said clamping jaw normally bearing upon said lip whereby its movement in one direction will be limited, a spring compressed rod carried by said pen holder, said spring compressed rod having an offset extension, said offset extension being fixedly secured to said clamping jaw whereby said clamping jaw will be urged in one direction for releasably retaining a pen point in engagement with said sleeve and said rod being adapted to operate so as to swing said clamping jaw forwardly and away from the clamping portion of said sleeve thereby permitting a pen point to be released.

90

In testimony whereof I hereunto affix my signature.

HENRY NEUMAN.
